US00D789931S

(12) **United States Design Patent** (10) **Patent No.:** **US D789,931 S**
(45) **Date of Patent:** **** Jun. 20, 2017**

(54) **VEHICLE DATA ACQUISITION DEVICE**

(71) Applicant: **Drew Technologies, Inc.**, Ann Arbor, MI (US)

(72) Inventors: **Michael Drew**, Dexter, MI (US); **Brian Herron**, Dexter, MI (US)

(73) Assignee: **DREW TECHNOLOGIES, INC.**, Ann Arbor, MI (US)

(**) Term: **15 Years**

(21) Appl. No.: **29/557,641**

(22) Filed: **Mar. 10, 2016**

(51) **LOC (10) Cl.** **14-02**

(52) **U.S. Cl.**

USPC **D14/357**

(58) **Field of Classification Search**

USPC .... D14/356-358, 388, 496, 137, 140, 140.1, D14/140.2, 155, 225, 226, 230, 240, 242, D14/243, 299, 300, 301, 302, 314, 328, D14/348, 349, 353, 354; D13/123, 158, D13/162, 162.1, 164, 168, 171-174, 184, D13/199; D10/46, 49, 75, 80, 103, 104.1 CPC G06F 1/00; G06F 1/1658; G06F 1/1656; G06F 1/1626; G06F 1/181; G06F 1/184; G06F 1/186; G06F 1/187; G07C 5/00; G07C 5/008; G07C 5/08; G07C 5/0808; G07C 5/0816; G07C 5/085; G07C 5/0858; G01D 5/00; G01D 5/12; B60R 16/0232

CLAIM

The ornamental design for a vehicle data acquisition device, as shown and described.

DESCRIPTION

FIG. 1 is a front perspective view of the vehicle data acquisition device of the present invention;

FIG. 2 is a front view of the vehicle data acquisition device shown in FIG. 1;

FIG. 3 is a rear view of the vehicle data acquisition device shown in FIG. 1.

FIG. 4 is a left side view of the vehicle data acquisition device shown in FIG. 1;

FIG. 5 is a right side view of the vehicle data acquisition device shown in FIG. 1.

FIG. 6 is a top view of the vehicle data acquisition device shown in FIG. 1; and,

FIG. 7 is a bottom view of the vehicle data acquisition device shown in FIG. 1.

The drawings include broken lines, which depict the portions of the vehicle data acquisition device that form no part of the claimed design.

1 Claim, 5 Drawing Sheets
